[57] CLAIM

The ornamental design for a bezel flashing sign, substantially as shown and described.

DESCRIPTION

FIG. 1 is a front elevational view of a bezel flashing sign incorporating my new design. The face has channels for movable letters.

FIGS. 2 and 3 are top plan and side elevational views thereof, taken in the directions corresponding to arrows 2 and 3 in FIG. 1. The Bezel flashing sign is symmetrical top and bottom, side to side. Hence, the bottom is the same as FIG. 2, and the opposite side is the mirror of FIG. 3. The back of the sign is flat and unornamented.

FIG. 4 is a top plan view of a modified form of a bezel flashing sign which is the same as the sign of FIGS. 1 to 3 except that it is two-sided.

FIG. 5 is a side elevational view of the sign taken in the direction of the arrow 5 in FIG. 4,

FIG. 6 is a front elevational view of another modified form of a bezel flashing sign which has a square rather than rectangular configuration and a different face for adhered rather than movable letters. In all other respects, the sign of FIG. 6 is similar to that of FIGS. 1 to 4. The back of the sign is flat and unornamented. The characteristic features of my design are the exposed flashing lamps and their outwardly sloping bezel mounting.

FIG. 1.

FIG. 2.

FIG. 3.

FIG. 4.

FIG. 5.

FIG. 6.
